US00D970606S

(12) **United States Design Patent** (10) **Patent No.:** **US D970,606 S**
(45) **Date of Patent:** **** Nov. 22, 2022**

(54) **PRINTER**

(71) Applicant: **BROTHER INDUSTRIES, LTD.**,
Nagoya (JP)

(72) Inventor: **Kazuhisa Tashima**, Nagoya (JP)

(73) Assignee: **BROTHER INDUSTRIES, LTD.**,
Nagoya (JP)

(**) Term: **15 Years**

(21) Appl. No.: **29/734,814**

(22) Filed: **May 15, 2020**

(30) **Foreign Application Priority Data**

Nov. 29, 2019 (JP) 2019-026544

(51) **LOC (13) Cl.** **14-02**

(52) **U.S. Cl.**

USPC **D18/50**

(57) **CLAIM**

The ornamental design for a printer, as shown and described.

DESCRIPTION

FIG. 1 is a perspective view of the printer;
FIG. 2 is a front elevational view thereof;

FIG. 3 is a top plan view thereof;

FIG. 4 is a left-side elevational view thereof;

FIG. 5 is a right-side elevational view thereof;

FIG. 6 is a rear elevational view thereof; and,

FIG. 7 is a bottom plan view thereof.

The evenly spaced broken lines depict unclaimed parts of
the printer and form no part of the claimed design.

1 Claim, 7 Drawing Sheets
